ELECTRIC CABLE

Philip Vassar Hunter and Leslie Giddens
 Brazier, London, and Harry Hill, Kent, England, assignors to Callender's Cable and Construction Company Limited, London, England, a British company

Application April 9, 1936, Serial No. 73,474
 In Great Britain April 16, 1935

6 Claims. (Cl. 174—25)

This invention relates to single core cables having a conductor usually, though not necessarily, of stranded form and a dielectric comprising a laminated body of insulation impregnated with a liquid or semi-liquid material, the layers of the insulation having, when seen in section at right angles to the conductor, a smooth non-circular form, such as described in the specification of U. S. Patent No. 1,906,968.

10 In accordance with the invention paper or other soft fibrous material is applied to the outer surface of the conductor to form a smoothing layer of small thickness and over this layer a smooth lapping of metal tape is applied to form a smooth, complete, non-circular, elastic, metal surface on which the dielectric is subsequently built up in the usual way. The whole of the cable structure, both inside and outside the layer of metal tape, is then impregnated by the usual procedures.

15 Under working conditions the metal tape will at convenient points, such as joints and terminations, be electrically connected with the conductor so that there is no electric field between the two. In general it appears preferable, but not 20 essential, to use a conductor of non-circular cross-section.

A helix of non-circular cross-section of resilient metal tape may be placed inside the smoothing layer of paper or other soft fibrous material.

30 This is lapped on the conductor either directly or with an intervening layer of soft fibrous material. In either case the resilient metal tape is not a close fit on the conductor or on the soft fibrous material but there is a small clearance so that 35 the tape is free to yield inwardly. This resilient tape forms a spring support for a few layers of paper or other soft fibrous material over which the smooth lapping of metal tape is applied.

Whether a resilient support is or is not incorporated in the fibrous smoothing layer applied to the surface of the conductor, the layer is such that it has the effect of smoothing out the surface irregularities due to the wires in the strand forming the conductor or to other causes so that 45 the outer surface of the layer has a smooth contour of regular form. The metal tape applied over the fibrous smoothing layer thus provides a metallic layer having a smooth regular contour without undulations corresponding to the positions of the wires at the surface of the strand.

50 The lappings of metal tape forming the non-circular metal surface on which the dielectric is built up must be carried out in such a way as to provide a complete covering, that is to say, so 55 that there are no openings between the turns

through which the surface of the underlying fibrous layer is exposed. It is also necessary to apply the tape in such a way that its edges do not project in a radial direction.

The invention will now be more fully described with frequent reference to the accompanying drawings which show examples of single core cable having cores constructed in accordance with the invention. In the drawings

5 Figure 1 is a perspective view of a length of 10 cable of which portions of the constituent parts have been successively removed to expose the structure of the cable.

15 Figure 2 is a cross-section of the cable shown in Figure 1 taken on plane at right angles to the longitudinal axis of the cable.

20 Figure 3 is a view similar to that of Figure 1 of a length of cable having a modified form of core construction.

25 Figure 4 is a cross-section of the cable shown in Figure 3 taken in a plane at right angles to the longitudinal axis of the cable and

Figure 5 shows a joint between the conductors of adjacent length of cable of the kind shown in Figures 1 and 2.

30 In both the illustrated examples the conductor 1 is of elliptical cross-section and of stranded form. In the cable shown in Figures 1 and 2 the conductor is directly enclosed in a soft fibrous layer 2 of small thickness. This layer is built 35 up of a suitable number of paper tapes, for instance, tapes of 5 mils thickness, applied helically in any convenient manner. The radial thickness of the layer will naturally depend to some extent upon the size and form of the strand. Over 40 this foundation layer is applied a metallic covering 3 consisting of two layers of metal tape each put on helically with only a small gap between adjacent turns and the adjacent layers being so disposed that the gap between the turns in one 45 layer coincides with the central region of the tape in the other layer. These tapes are smooth surfaced bronze tapes of 3 mils thickness and about 200 millimetres width. Naturally tapes of other sizes and material may be used providing they 50 have a smooth surface and are sufficiently thin to be flexible; for instance, copper tape of about 3 mils thickness may be used. Also the metal layer may comprise more than two tapes or it may consist of a single tape only. In the latter 55 event, it is desirable to give it a special treatment to ensure that neither initially nor after bending of the cable are there any projecting edges, such as are liable to be produced by applying a metal tape in a single layer with substantial lap, it being

understood that overlapping is necessary in order to ensure complete enclosure by the layer of the material within it. In order to get the desired smooth surface it is necessary in this case to stretch that part of the tape which will, when applied, overlap the adjacent turn. This stretching should of course be proportionate to the increase in periphery produced by the application of a thickness of the tape to the underlying layer.

10 The stretching is preferably carried out as the tape is being applied in position round the conductor. In all cases however the metal tape should be applied with considerable tension so that the inner surface is in close contact with the underlying material and the overlapping parts of the tape or tapes are also in close contact.

Over the smooth, complete, elastic, metal surface of elliptical cross-section thus formed is built up the laminated dielectric body 4 of paper tape. This is enclosed in a conductive layer 5 which makes contact with the circular lead sheath 6 in the region of the major axis of the core. The spaces between the insulated core and the sheath are filled with gas or, alternatively, they may be filled partly with gas and partly with impregnating oil or compound and the whole of the fibrous material within the lead sheath is impregnated with insulating oil or compound by any suitable known process. The sheath 6 is provided with a protective covering 7 of impregnated fibrous material. Alternatively the outer part of the cable may be of other form, for instance, any of the other forms described in the specification of the aforesaid patent.

In the example of construction shown in Figures 3 and 4, directly over the strand 1 of elliptical cross-section is wrapped a tape 9. This is of bronze and is 7 mils thick and 200 millimetres wide. As is clear from Figure 4, this tape is not applied so tightly that it lies in contact with the entire surface of the strand 1 but is so applied as to leave a small clearance 10 on each side of the strand so that it may constitute a resilient base for the overlying layers 2 and 3 of paper and metal respectively. Naturally the resilient tape may be of other suitable metal and be of any suitable thickness, for instance, from 5-10 mils thick. The smoothing layer 2 of paper consists of three layers of tape, each put on with a small gap between adjacent turns and the adjacent layers being so disposed that the gap of one layer is overlapped to a substantial extent by the tape of the succeeding layer. It will be appreciated that the thickness of the paper smoothing layer may be reduced owing to the smoothing action of the resilient tape 9. Alternatively, of course, the resilient tape may be applied as an open helix with a gap up to about 50% of the width of the tape. In this case the number of layers of paper or other fibrous material then applied is increased to ensure a thickness sufficient to bridge the gap and provide a smooth surface on which the smooth metallic covering 3 consisting of two layers of metal tape may be applied as described with reference to Figures 1 and 2. The construction of the dielectric and the surrounding part of the cable shown in Figures 3 and 4 is similar to that of the cable shown in Figures 1 and 2 and will not be further described.

Figure 5 shows a method of effecting a conductor joint and of uniting the metallic smoothing tapes to the conductor. The ends of adjacent

lengths of cable are prepared by cutting back the outer coverings and the dielectric for appropriate distances. The metallic tapes forming the surface 3 are then uncoiled and temporarily bent back. The underlying layer 2 of paper is then cut back to expose the conductor, the wires of the outer layer of which are cut back also. The ends of the inner part of the two conductors are jointed by the aid of a ferrule 12 and soldering. The tapes 3 are then wrapped over the soldered joint and secured to the conductor and ferrule by soldering metal 13. It will be observed that the outer shape and dimensions of the ferrule approximate to the inside of the layer 3 of metal tape so that there is no step or break in the contour of the conductor through the joint. If it is desired to obtain this advantage without cutting back the outer wires of the conductor, the thickness of the layer 2 of paper may be increased and/or the thickness of the ferrule 12 may be reduced to make the thickness of the layer 2 and that of the ferrule correspond.

It has been found, other things being equal, that the improved construction gives the wall of dielectric an increase in effective strength of about 50% as compared with a wall of similar thickness applied directly to the stranded conductor.

It is believed that this improvement is due, not only to the smoothing out of the contour of the inner conductive surface to which the whole dielectric is applied, but also to the fact that the new surface provided by the layer of metal tape has other properties. It is in effect a conductor with a smooth non-circular elastic surface which, under the influence of internal pressure due to the expansion of its inner part under heat, can change its shape and thereby transmit a force to and move with the inner layers of the wall of the dielectric. For this reason, the invention may be applied to solid conductors as well as to those formed of wires stranded together.

What we claim as our invention is:

1. A single core electric cable comprising a conductor, a smoothing layer of small thickness surrounding said conductor and consisting of soft fibrous material, a complete, elastic, smooth surfaced, metal layer of non-circular cross-section enclosing said smoothing layer and consisting of at least one helical lapping of metal tape, impregnating fluid in the interstices in the structure enclosed by said metal layer, an impregnated laminated body of insulation built up on said metal layer, and an impervious sheath surrounding said laminated body of insulation. 55

2. A single core electric cable comprising a conductor, a smoothing layer of small thickness surrounding said conductor and consisting of soft fibrous material, a spring support of non-circular cross-section disposed inside said smoothing layer, a complete, elastic, smooth-surfaced, metal layer of non-circular cross-section enclosing said smoothing layer and consisting of at least one helical lapping of metal tape, impregnating fluid in the interstices in the structure 60 enclosed by said metal layer, an impregnated laminated body of insulation built up on said metal layer and an impervious sheath surrounding said laminated body of insulation. 65

3. A single core electric cable comprising a conductor, a helix of non-circular cross-section of resilient metal tape directly surrounding said conductor with a small clearance between it and the conductor, a smoothing layer of small thickness surrounding said helix and consisting of soft 70

fibrous material, a complete, elastic, smooth-surfaced, metal layer of non-circular cross-section enclosing said smoothing layer and consisting of at least one helical lapping of metal tape impregnating fluid in the interstices in the structure enclosed by said metal layer, an impregnated laminated body of insulation built up on said metal layer, and an impervious sheath surrounding said laminated body of insulation.

5 4. An electric cable system comprising a single conductor, a smoothing layer of small thickness surrounding said conductor and consisting of soft fibrous material, a complete, elastic, smooth-surfaced metal layer of non-circular cross-section enclosing said smoothing layer and consisting of at least one helical lapping of metal tape, said layer being electrically connected to said conductor at intervals, impregnating fluid in the interstices in the structure enclosed by said

10 metal layer, an impregnated laminated body of insulation built up on said metal layer, and an impervious sheath surrounding said laminated body of insulation.

15 5. A single core electric cable comprising a conductor, a smoothing layer of small thickness surrounding said conductor and consisting of soft

fibrous material, impregnating fluid in the interstices in said conductor and in said smoothing layer, a smooth walled, elastic, metal tube of non-circular cross-section which consists of at least one helical lapping of metal tape and which encloses said conductor and said smoothing layer and is responsive to variations in the volume of said impregnating fluid, an impregnated laminated body of insulation built up of said tube, and an impervious sheath surrounding said laminated body of insulation.

6. A single core electric cable comprising a conductor, a smoothing layer of small thickness surrounding said conductor and consisting of soft fibrous material, a complete, elastic, smooth-surfaced, metal layer of elliptical cross-section enclosing said smoothing layer and consisting of at least one helical lapping of metal tape, impregnating fluid in the interstices enclosed by said metal layer, an impregnated laminated body of insulation built up on said metal layer, and an impervious sheath surrounding said laminated body of insulation.
